TOOL USED IN FITTING A TIRE TO A WHEEL

John Anthony Holdsworth, Redditch, England,
assignor to Dunlop Limited

Filed Dec. 5, 1973, Ser. No. 421,811

Claims priority, application Great Britain June 15, 1973

Term of patent 14 years

Int. Cl. D8—03

U.S. Cl. D8—31

FIG. 1 is a side view of my new design for a tool used in fitting a tire to a wheel.

FIG. 2 is a plan view thereof.

FIG. 3 is an end view in the direction of the arrow of FIG. 1.

I claim:

The ornamental design for a tool used in fitting a tire to a wheel, as shown.
